(57) **CLAIM**

The ornamental design for a harpoon applicator tip, as shown and described.

DESCRIPTION

FIG. 1 is a front left perspective view of a harpoon applicator tip showing my new design;

FIG. 2 is a front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken line showing of a shaft portion of the harpoon applicator tip is for the purpose of illustrating environmental structure and forms no part of the claim design. The broken lines also define the boundary between the claimed design and the environmental structure and form no part of the claimed design. The broken away portion of the shaft indicates that the shaft is of indeterminate length.
